UNITED STATES PATENT OFFICE.

JOHN ROWBOTHAM, OF NEWARK, NEW JERSEY.

DESIGN FOR BUTTONS.

SPECIFICATION forming part of Design No. 11,675, dated March 9, 1880.

Application filed February 6, 1880. Term of patent 3½ years.

To all whom it may concern:

Be it known that I, JOHN ROWBOTHAM, of Newark, in the county of Essex and State of New Jersey, have invented a new and Improved Design for Buttons, of which the following is a specification.

The drawing represents a plan of the new design for buttons.

The leading feature of my design consists in a square figure formed on the face of the button about the central hole thereof by parallel rows of small square indentations, and said indentations may be colored or stained of any color.

15 A represents the button, having a central

hole, a, and b b are the square indentations arranged in the form of a square, B, about the said central hole, a.

Having thus described my invention, I claim as new and desire to secure by Design 20 Patent—

The design for a button herein shown and described, the same consisting of a square figure centrally formed on the face of the button by parallel rows of square indentations.

JOHN ROWBOTHAM.
